REAR VIEW MIRROR

Noel M. Torres, 2826 Larkin Place,
San Diego, Calif. 92123

Filed July 3, 1968, Ser. No. 12,609

Term of patent 14 years

Int. Cl. D12—14

U.S. Cl. D14—6

Fig. 1

Fig. 2

Fig. 3

Fig. 4

Fig. 5

FIGURE 1 is a perspective view of a rear view mirror, showing my new design;

FIGURE 2 is a top plan view thereof;

FIGURE 3 is an elevational view as taken from the rear of FIGURE 1;

FIGURE 4 is an end elevational view as taken from the right hand end of FIGURE 3; and

FIGURE 5 is an end elevational view as taken from the left hand end of FIGURE 3.

I claim:

The ornamental design for a rear view mirror, as shown.
